CARBURETOR

Filed Sept. 12, 1928

UNITED STATES PATENT OFFICE

CHARLES H. KIRBY AND FREDERICK PURDY, OF FLINT, MICHIGAN, ASSIGNORS TO
MARVEL CARBURETER COMPANY, OF FLINT, MICHIGAN, A CORPORATION OF
ILLINOIS

CARBURETOR

Application filed September 12, 1928. Serial No. 305,528.

This invention relates to improvements in carburetors of the character used for furnishing explosive mixtures to internal combustion engines.

5 The primary object of the invention is to furnish a carburetor of the Venturi throat type with adjustable means for creating variable depression or vacuum in chambers communicating with the fuel feeding device 10 or devices.

Another object of the invention is to provide a carburetor Venturi throat having an opening in its entrance lip, and a ported rotatable member cooperating with said opening to create a depression in a chamber or passageway communicating with the fuel feeding device or devices; said ported member being adjustable for varying the degree of vacuum.

20 It has heretofore been proposed to provide a carburetor with a plurality of fuel feeding passageways, one communicating with the mixture conduit, posterior to the throttle valve, and the other formed by the main nozzle of the carburetor. Such passageways 25 communicating with an opening in the entrance lip of the Venturi tube or throat, and consequently when the throttle is moving toward open position, the velocity of the air flowing through the venturi will be increased, with the result that the vacuum created 30 through the opening in the entering lip of the venturi will be increased, to retard the flow of fuel through said passageways. In

35 such construction, a relatively small stream of fuel is discharged into the mixture passageway above the throttle, which discharge is variable with relation to the position of the throttle, but does not cease altogether in any position of the throttle. This stream is mingled with that of the main nozzle when the throttle is open to any extent, and it diminishes as the discharge of the main nozzle increases; being modified in its extent by a 40 slightly sub-atmospheric pressure in a chamber communicating with the stream passageway; this sub-atmospheric pressure being due to the position of the opening or port in the entering lip of the Venturi sleeve, and its 45 influence being greater as the velocity of the

air entering the Venturi sleeve is increased.

It is a further object of this invention to improve carburetors of the last mentioned type by elongating the port in the entrance lip of the venturi, and extending a rotatable 55 sleeve with a smaller port therein, into the venturi, in such a way that the sleeve forms a portion of the surface of the entering lip of the venturi. As the ported sleeve may be turned for adjustment purposes, the port of the latter may be shifted toward or away 60 from the lower edge of the venturi, and in this way, the suction exerted through the ported sleeve may be varied.

A further object is to furnish a construction 65 of this character in which the radius of the entering lip of the venturi is the same as the radius of the ported tube, whereby the tube in shifting around the lip radius, may place its port in various angular positions to 70 influence the operating depression.

With the above objects and with other objects in view which will appear as the description proceeds, the invention consists in the 75 novel features hereinafter described in detail, illustrated in the accompanying drawing, and more particularly pointed out in the appended claims.

Referring to the drawing,

Fig. 1 is a vertical sectional view of an embodiment of a carburetor devised especially to facilitate the disclosure of the invention, and showing the relative fuel levels in the various nozzles or stand pipes, when the 80 throttle is in fully closed position.

Fig. 2 is a horizontal sectional view, taken on line 2—2 of Fig. 1.

Fig. 3 is an elevation, partly in vertical section, of a detail, indicating the manner of placing the adjustable port of the venturi 90 in communication with the chambers to be subjected to sub-atmospheric pressure.

Fig. 4 is a vertical sectional view, taken on line 4—4 of Fig. 3.

While the invention has been illustrated in 95 connection with a carburetor of a particular type, it will be obvious that it may be embodied in carburetors of various types, or in any carburetor where it is desired to utilize 100 the velocity of air flowing through a venturi

to create variable sub-atmospheric pressure in a chamber for modifying or controlling the flow of fuel or the like.

In the drawing, it will be noted that the fuel is fed from any suitable float tank 1, directly to a tube 2, having a nozzle 3, through which a fine stream is fed into an annular chamber 4, the outlet 5 of which is controlled by a needle valve 6. This fuel constantly flows through a duct 7, under suction influence exerted in the carburetor outlet 8. The duct 7 opens into this passageway or outlet, posterior to the throttle valve 9, and consequently, fuel will be continuously fed through 10 2 and 7, due to suction from the engine.

Fuel from the float tank, also flows through an orifice member 10, and by this means, in regulated quantity, enters a passageway 11, from which it flows through another orifice 20 member 12, into a U-shaped conduit 13. A needle valve or the like 14, controls the flow to the U-shaped conduit, and the arms of this conduit communicate with the main nozzle 15, and an auxiliary nozzle 16; the latter being 25 located within a chamber 17.

The main nozzle outlet terminates within a Venturi sleeve 18, located in the mixture passageway, as is usual in some types of carburetors. A port 19 is located in the entrance 30 lip of the Venturi sleeve, and in a construction heretofore proposed, such port communicated by a passageway 20 with the chamber 17, as well as with a chamber 21, in which the tube 2 is located. Due to such arrangement, suction influences exerted through 19, normally retarded the flow of fuel from the nozzle 16, and also had a modifying tendency on the flow of the fuel passing through duct 7, tending to diminish the flow through 7, 35 when the flow through the main nozzle is increased.

Such carburetor was also equipped with an auxiliary well 22, containing a tube 23, into which the fuel arose from conduit 11, by way 45 of passageway 24. The top of the tube 23 is capped and provided with an orifice member 25, the hole in which is of less diameter than the tube 16, whereby under acceleration, when the main fuel nozzle begins to draw on the auxiliary supply, it will first empty the nozzle 16, and afterwards, the well 23, such emptying being brought about during the movement of the throttle from closed to fully opened position.

55 The present invention pertains to improvements in the means for placing the port 19 in communication with the passageway 20. In the construction heretofore proposed, there was no means for varying the position of the port 19 relatively to the entrance lip of the venturi, and consequently, the suction influences would always be the same under given conditions. With the present invention, the opening in the Venturi lip may be 60 shifted in order that the angular position of

this hole may influence the operating depression. To this end, a cylindrical bore 30 is cut through the body of the carburetor, and Venturi tube 18, and the periphery of this bore coincides with the curvature of the entrance lip of the venturi. In this bore, a cylindrical sleeve 31 is placed, having a radius the same as the radius of the entrance lip of the venturi, so that an intermediate portion of the periphery of the tube extends through the opening 19. A relatively small aperture 32 extends through the cylindrical wall of the tube, on a line coinciding with the elongated opening 19, whereby when the tube is rotated, the aperture 32 will be shifted toward or away from the lower edge of the venturi.

Some suitable means must be provided to place the interior of the tube 31 in communication with the passageway 20, and one expedient for this purpose is shown in the drawing. It consists of a U-shaped pipe 33 having one of its ends extending into the tube 31, and its other end extending into a duct 34 which communicates with the passageway 20.

For the purpose of shifting the tube 31, it is provided with a stem or shaft 35 which extends through the wall of the carburetor, and is provided at its outer end with a hand 36 that is fast on the shaft and designed to cooperate with a suitable scale formed on an indicator plate 37 that is secured to one side of the carburetor in a stationary manner, for instance, by means of a screw 38.

From the foregoing, it may be seen that the discharge through 7 will vary as the throttle 9 moves, but will not cease altogether in any position of the throttle. When the throttle is fully closed, the supply through 7 will be at a maximum, but as the throttle opens, this supply will be diminished. As before stated, it diminishes as the discharge from the main nozzle increases, and it is modified in its extent by a slightly sub-atmospheric pressure in the chamber 21, due to the position of the aperture 32 in the entering lip of the Venturi sleeve. This sub-atmospheric influence is greater as the velocity of the air entering the venturi is increased, but it is 110 obvious that such influence may be varied by turning the tube 31, so as to raise or lower the aperture 32.

Instant acceleration in the type of carburetor illustrated, is obtained by the U-tube, 115 made up of the nozzle 15, stand pipe 16, and passageway 13; the fuel discharge rate being modified by the depression or sub-atmospheric pressure in the passageway 20, so that the higher the speed of the motor, the 120 less the additional discharge for acceleration purposes.

The well 23 is for the double purpose of 125 prolonging the accelerating charge, and for "thinning out" the mixture at high speeds.

It is believed that the invention may be readily understood from the foregoing description when read in connection with the accompanying drawing, and it is obvious that various changes may be made in the details disclosed, without departing from the spirit of the invention, as expressed in the claims.

What we claim and desire to secure by Letters Patent is:

1. In a carburetor having a main passage-way controlled by a throttle valve, a Venturi throat in said passageway, an opening in the entrance lip of the Venturi throat, a ported member movably mounted relatively to the Venturi throat and having its port arranged to register with and shift relatively to the opening in the entering lip of the venturi, a chamber to be subjected to sub-atmospheric pressure, and means placing the port of the ported member in communication with said chamber.
2. In a carburetor, a Venturi throat having an opening in its entrance lip, a shiftable member extending into a wall of said throat and having a curved wall provided with a port shiftable relatively to the opening in the entrance lip of the venturi when said member is turning, a chamber to be subjected to sub-atmospheric pressure, and means placing the chamber in communication with said port.
3. In a carburetor, a Venturi throat having a curved entrance lip provided with an opening, a turnable cylindrical member extending into a wall of the Venturi throat, and having a ported portion extending through said opening, a chamber to be subjected to sub-atmospheric pressure, and means placing said chamber in communication with said port.
4. In a carburetor, a Venturi throat having a curved entrance lip provided with an opening, a cylindrical tube rotatably mounted in the Venturi throat and having a ported portion extending through said opening, the radius of the tube being substantially the same as the radius of the surface of said entrance lip, a chamber to be subjected to sub-atmospheric pressure, and means placing the interior of the tube in communication with said chamber.
5. In a carburetor, a Venturi throat having an entrance lip provided with an opening therein, a cylindrical tube rotatably mounted in a wall of the throat and having a ported portion extending through said opening, means for turning said tube, means for indicating exteriorly of the carburetor, the position of the port, a chamber to be subjected to sub-atmospheric pressure, and means placing said chamber in communication with the interior of said tube.

In testimony whereof we hereunto affix our signatures.

CHARLES H. KIRBY.
FREDERICK PURDY.
